LA ROUX B. GIDDENS, OF TAMPA, FLORIDA

CARBURETER ATTACHMENT.

1,913,691.

Specification of Letters Patent. Patented Jan. 23, 1917.

Application filed August 16, 1915. Serial No. 45,783.

To all whom it may concern:

Be it known that I, LA ROUX B. GIDDENS, a citizen of the United States, residing at Tampa, in the county of Hillsboro and State of Florida, have invented certain new and useful Improvements in Carbureter Attachments; and I do hereby declare the following to be a full, clear, and exact description of the invention, such as will enable others skilled in the art to which it appertains to make and use the same.

The present invention relates to improvements in carbureter attachments, and has for an object to provide an improved device adapted for placement in the intake pipe of internal combustion or other engines, and operating to subject the combined fuel and air issuing from the carbureter to an agitating action in order to promote a more homogeneous mixture.

It is another object of the present invention to provide a device of the above character which will be mounted on a frame adapted for detachably fitting in the intake pipe of the engine, and which will be constructed to be located in close proximity to the throttle valve and not interfere with the operation thereof.

Reference is had to the accompanying drawings, in which similar parts are indicated by similar reference numerals throughout the several views.

Figure 1 is a fragmentary elevational view of a carbureter with the engine intake pipe shown in section, and having the improved attachment shown attached thereto, partly in elevation and partly in section; and Fig. 2 is a perspective view of the improved attachment.

Referring more particularly to the drawings, wherein one embodiment of the present invention is illustrated, 1 designates a carbureter which may be of any suitable approved type, and 2 and 3 designate adjacent sections of the intake pipe of an internal combustion or other engine.

In the section 2 of the intake pipe is located the usual throttle valve 4 which is connected up to be actuated from any of the mechanisms now employed for this purpose. The sections 2 and 3 of the intake pipe are provided with circular or other flanges 5 and 6, respectively, between which is clamped a gasket 7, and which are secured together by bolts or the like 8.

The improved mixing device as more par-

ticularly seen in Fig. 2 is built up of a frame comprising a cross bar 9, bent at its opposite ends to provide flanges 10 and 11 for snugly embracing the interior of the pipe section 3, and the lower edges of said flanges are reduced and bent angularly into lugs 12 and 13, arranged to be received between the flanges 5 and 6 of the pipe sections, and which are embedded in the soft material of the gasket 7 when the bolts 8 are tightened.

As disclosed in Fig. 2, the bar 9 is preferably of the configuration illustrated, wherein the central portion is relatively thick and where is mounted a spindle 14 extending up within the pipe section 3. On the spindle 14 are journaled to rotate one or more fans including hubs 15 and 16 having vanes 17 and 18, the latter being preferably disposed reversely so as to be rotated in opposite directions on encountering the current of the charge passing through the intake pipe on its way to the engine.

The hubs 15 and 16 of the mixing fans are removably secured in place by a collar 19 secured to the spindle by a pin, screw, or other suitable means 20. The construction of the removable frame permits the improved attachment to be connected between the flanges of the pipe sections 2 and 3 as now at present constructed and in close proximity to the throttle valve 4, but at the same time not interfering with the free operation thereof.

As the charge issues from the carbureter past the throttle valve 4, and through the intake pipe, the same will encounter the vanes 17 and 18 of the mixing fans, which will be rotated in opposite directions due to the reverse disposal of the same, and will subject the charge to an agitating action which will promote a more intimate and homogeneous mixture.

The device can be readily removed by separating the pipe sections 2 and 3 when the bar 9 can be grasped and moved axially of the section 3. Similarly, the device can be readily attached, and the fans detached and replaced on the spindle 14 by withdrawing the collar 19.

I am aware that mixing devices for substantially the same purpose, and embodying pairs of fans provided with reversely-disposed blades for rotation in opposite directions by the charge, have been hitherto proposed and patented, and I do not wish myself understood as claiming this combination broadly.

I have illustrated and described preferred and satisfactory constructions, but obviously changes could be made in the combination and arrangement of parts without departing from the spirit of my invention.

I claim:-

1. In a device of the character described, the combination with an intake pipe having flanged adjacent sections, of a single bar, integral flanges bent from said bar and fitting in one pipe section, integral lugs bent outwardly from said flanges and extending between the flanges of the pipe sections, and a rotary mixing device mounted on said bar, substantially as described.
- 10 2. In a device of the character described, the combination with an intake pipe having

flanged adjacent sections, of a single straight bar fitted diametrically across one pipe section and having its ends bent to provide flanges frictionally gripping the interior walls of said section, the extremities of said bar beyond the flanges being turned outwardly to constitute lugs engaging between the flanges of the pipe sections, a spindle mounted on said bar, and a pair of fans journaled on said spindle, and having reversely-disposed vanes for rotation in opposite direction under the influence of the incoming charge, substantially as described.

In testimony whereof, I affix my signature.

LA ROUX B. GIDDENS.
